ROCK CRUSHER

Percy W. Palmer, Edgerton, Wis.

Application June 27, 1938, Serial No. 215,984

2 Claims. (Cl. 83—12)

My invention relates to improvements in rock crushers.

Rock crushers or crushers for handling substances presenting similar problems are generally classifiable into three general types known as "jaw crushers," "gyratory crushers," and "rotary" or "roll" type crushers. My invention relates to improvements in either type but more particularly to the last named or roll type.

Roller type crushers have heretofore comprised relatively smooth-faced rolls mounted upon substantial bearings whereby the rolls are held approximately horizontally and with the axes of the rolls in approximately the same horizontal plane. The peripheries of the rolls are spaced according to the degree of fineness of crushed material desired. The rolls are power driven and usually rotate at approximately the same speed.

Aggregate material fed to the rolls for crushing is usually graded to a size receivable into that portion of the valley between the rolls which is known as the "nip." This is the zone in which the particular size of aggregate is seized between the converging surfaces of the rolls.

If the rolls used in the previously known roller type crushers are of large diameter the converging faces of the rolls at the nip will be more nearly parallel to one another, but if the rolls are of comparatively small diameter, the opposed surfaces of the rolls at the nip are so divergent as to require that the aggregate be accurately sized. Even then there is a marked tendency for smooth or odd shaped pieces of aggregate to evade the nip and to frictionally ride upon the surfaces of the rolls so as to score them deeply and to also blockade the flow of aggregate into the nip of the rolls, thus resulting in inefficiency of operation and rapid destruction of the surface of the crushing rolls.

The object of my invention is to provide in crusher rolls of comparatively small diameter, a configuration of the face of the rolls whereby the portions of such faces opposed to each other at the nip of the rolls are more nearly parallel, and in accomplishing this object I form the face of a crusher roll in a step-like configuration. I also mount my improved crusher rolls in a supporting structure whereby to provide for positive drive of the rolls at identical speeds so that one flat step upon one of the rolls as it approaches the nip is faced by an opposed step of the other roll, and these faces of these opposed steps are much more nearly in parallelism with one another than

would be the arcuate surfaces of rolls having identical small diameters.

Another object of my invention is to provide crusher rolls of comparatively soft and comparatively inexpensively manufacturable material, and to provide for such rolls a crushing face or series of crushing face plates which are of special alloy steel especially suited to the crushing operation and easily removable from the general structure of the crushing roll for repair or renewal of the crushing face.

Another object of my invention is to provide crusher rolls with a step-like configuration, or a configuration suited to receive plates which will provide such a step-like configuration whereby the plates disposed in such step formation are braced against one another, and are braced against the general structure of their respective rolls, thus providing for long life of the rolls.

A further object of my invention is to provide improved structure for crushing an aggregate wherein the aggregate contacting portions of the mechanism are so disposed that in "retreating" from the crushing zone they rapidly open the throat whereby to quickly release the crushed material.

In the drawings:

Figure 1 is a view of two opposed rolls of a cylindrical crusher embodying the step-like configuration of my invention.

Figure 2 is a series of diagrammatic views of progressing aggregate engaged by opposed portions of crushing rolls embodying my invention; the first view showing a piece of aggregate at the "nip"; the second view showing the aggregate in the institution of the crushing action; the third view showing the aggregate in the completion of the crushing operation; and the fourth view showing the aggregate in the outlet of the throat as the crushed aggregate is delivered by the rolls.

Figure 3 is a section of a portion of the supporting shaft hub and rim of a crusher roll with my improved working face therefor.

Figure 4 is an end elevation of two of my crusher rolls, and the supporting bearing structure therefor.

Figure 5 is an enlarged detail view showing portions of the two rolls shown in Figure 1, said portions disclosing the relation of the opposed meeting portions of the rolls.

Figure 6 is a perspective of a special bolt used in the attachment of my crusher face to a wheel frame.

Like parts are designated by the same reference characters throughout the several views.

Crusher rolls 10 and 11, made in accord with my invention, are provided with a step-like external configuration shown clearly in Figures 1, 2, 4, and 5 of the drawings whereby to present lands 12 with shoulders 13 de-marking them. I may either form the surface structure of my crusher rolls as one cylindrical piece, as shown 10 in Figure 1, or I may provide plates 14 of special alloy hardened steel which are secured in place against shoulders 13 and against their associated plates by means of bolts 15 or other suitable devices, as shown in Figure 6.

15 Disposition of the lands 12 and the shape of the plate-like surfaces is such that the faces of the plates at the point of the nip between the rolls are approaching parallelism with each other, and in any event, are more nearly parallel with 20 each other than would be the cylindrical faces of smooth rolls.

The lands or plates in advance of the position shown at 16, in other words as shown in Figures 2 and 5, may be said to be in "the crushing zone." 25 Here the lands or plates are substantially parallel and the crushing operation is instituted. At 18 the lands or plates are opening slightly in the throat of the rolls and by the time they are in the position shown at 19 the throat is opened 30 rapidly and the aggregate is free of the rolls.

The general construction to provide the proper surfaces to carry out my invention may either include the casting of complete cylinders to be affixed upon a supporting hub and spoke structure 35 as shown in Figure 1, or I may provide a basic cylindrical structure as shown in Figures 3 and 5 upon which separate plates 14 may be attached. Thus upon the lands 12 and against the shoulder 13 I provide hardened plates 14 of special alloy 40 hardened steel which are secured in place against the shoulders 13 and against their associated plates by means of bolts 15 or other suitable devices, as for instance, rivets, although I have found that bolts as shown in the drawings and 45 shaped as shown in Figure 6, are best suited to this work.

Obviously, the complete cylinders shown in Figure 1 are of the proper alloy steel and may be mounted upon supporting structure of softer and 50 less tough material.

My rolls 10 and 11 equipped with face plates 14 may be mounted upon a supporting structure 20 as indicated in Figure 4 so that a fixed bearing 21 for roll 10, and an adjustable bearing 22 55 for roll 11 will support the respective rolls in opposed crushing relationship under the urge of a spring 23 which will permit of only slight movement of the roll 11 under the most severe crushing stress.

60 The rolls 10 and 11 may be supported by bearing 24 and 22 upon a shaft 100 or 110, respectively, and power to rotate the rolls, in the direction indicated by arrows may be applied in any suitable manner to drive the rolls at identical 65 speed of rotation.

In Figure 1 I have shown a cylindrical crusher roll 30 with a smooth cylindrical face 31 upon

which a complete cylindrical working face 32 may be bolted—such cylindrical face being pre-cast or pre-formed to provide plate-like surfaces corresponding in shape and function to the faces 16 at the nip of the crusher rolls. In the use of 5 either of the alternative structures, a hub 112, with its spokes 113, and the cylindrical body 114 of the roll, may be made of any relatively tough, relatively soft steel or other suitable material for receiving the face plates 14 of the cylindrical 10 member 32 which will provide alloy steel of hardness to sustain the stresses of the rock crushing operation.

From the above description and directing attention now to Figure 2, it will be seen that aggregate entering into the nip of the rolls is received between faces 16 and that the tendency of the aggregate to evade the nip is reduced markedly by the step-like configuration of the rolls. Faces 16 are approaching parallelism and 20 tend to hold the aggregate. As the crushing action proceeds, as shown in the second view in Figure 2, the plates accompanying the crushing action are substantially parallel. They assume actual parallelism as shown in the third view in 25 Figure 2 and the crushing action is substantially completed at this point although the trailing corners of the plates come closer together as shown in Figures 2 and 5. Finally the plates in the position 19 are opened rapidly and the throat is 30 cleared of crushed material much more rapidly than smooth rolls could accomplish this purpose.

I claim:

1. In a crusher including elements having opposed generally arcuate surfaces power connected 35 to provide equal surface velocities and respectively mounted for arcuate movement downwardly toward the bite of a crushing zone, a straight step-like configuration for said surfaces, the steps thereof being parallel to the axis of the 40 arcuate crushing surface and being substantially plane and tilted with respect to said arcuate surfaces so that opposing steps approaching the bite of the crushing zone are more nearly in parallelism than the general arc of said surfaces, the substantially radial surfaces of the step-like configurations of the two rolls being positioned to lie simultaneously in the plane of the axis of the 45 arcuate surfaces.

2. In a crusher including elements having opposed generally arcuate surfaces mounted and power connected whereby to be respectively arcuately movable downwardly toward a bite of a crushing zone, a step-like configuration for said surfaces, the steps thereof being substantially 55 plane and tilted with respect to said arcuate surfaces so that opposing steps approaching the crushing zone are more nearly in parallelism than are said arcuate surfaces, said stepped surfaces being supported and motivated for synchronous 60 movement and identical surface speed to move said stepped surfaces downwardly into said bite with the substantially radial surfaces of the step-like configurations lying simultaneously in the 65 plane of the axis of said arcuate surfaces.

PERCY W. PALMER.
